MEANS FOR FORMING ZONES OF VARYING AND VARIABLE STRENGTHS IN MAGNETIC FIELDS.

1,132,016.

Specification of Letters Patent. Patented Mar. 16, 1915.

Application filed January 24, 1912. Serial No. 673,131.

To all whom it may concern:

Be it known that I, AUGUST F. JOBKE, a citizen of the United States of America, residing at Wilkinsburg, in the county of Allegheny and State of Pennsylvania, have invented certain new and useful improvements in Means for Forming Zones of Varying and Variable Strengths in Magnetic Fields, (Case I,) of which the following is 10 a specification, reference being had therein to the accompanying drawing.

My invention relates to improvements in means for forming zones of varying and variable strengths in magnetic fields, relating more particularly to the formation 15 of the magnet poles which produce the magnet fields or gaps.

So far as I am aware, the only attempts which have been made to vary the field 20 strength of a magnetic gap have embodied the idea of changing the distances between the pole pieces which form the gap, this difference or variation being provided either by adjusting one or most of the pole pieces 25 in directions toward and from each other, by employing pole pieces adapted to divide the magnetic field into several fields each of the divided poles occupying a position to increase or diminish the distance between 30 the two poles from each of the other divided poles; or to employ this latter idea with each of the divided poles adjustable to permit of variations in such distance.

Any arrangement which involves a 35 change in the distance between opposing poles of a gap is disadvantageous for the following reasons: Assuming, for example, the provision of two opposing pole pieces, one involving a structure having a plane flat 40 surface or face, with the other in the form of a plurality of wedges, the edges of the wedge form being spaced at different distances from the flat face of the other pole, an example of which is shown in Figure 6 of 45 the drawing, and to which reference may be had in connection with this discussion, the showing therein made providing for three zones of varying strength. It should be noted that this particular form represents approximately the greatest value 50 heretofore known in this special type of apparatus. As will be seen by reference to

said figure, the zone of greatest strength is that provided by the edge in closest proximity to the opposite pole piece, while that 55 on the right, being the greatest distance from the opposite pole piece provides the zone of least strength, the intermediate zone having a strength between the outer zones. As will be seen, each zone has its lines of 60 force converging from the flat pole face to the opposing edge, with the face occupied by each zone on the flat face approximately the same width. As will be seen by the lines connecting the opposite poles, the field of 65 greatest strength, has in accordance with the well known physical law that the greater the convergence of the angles representing the lines of force passing toward a point, such as that of an edge, within certain limits, the greater will be the magnetic attraction, it being understood that where an angle of convergence is unduly increased, as by decreasing the distance between the opposing poles, the advantage gained by the 70 increase in the angle of convergence will be overcome by an increase in stray flux, so that a loss in flux is provided with a resultant waste. On the contrary, however, where the angle of convergence is decreased, 75 as by increasing the distance between the poles, the field is not only weakened in strength, but in addition, the lines of force will provide a different form of field, the lines bulging owing to the repellent action 80 of similar polarity, the lines of force closely approaching exact parallelism and of almost uniform density, with a consequent result that there is no pull or attraction in either direction on a plane intersecting at right 85 angles and centrally the space between two opposing poles, each of which is wedge-shaped with the edges in opposition to each other, such plane corresponding to the flat face of the lower pole in said figure, this 90 attraction increasing from zero on that face to its maximum at the pole edge; where a structure of this type is used in magnetic ore separation, it will be readily understood that where the distance between 95 the poles is increased in this manner there may result a condition where a strong flux will be provided but without any or but very little pull or attraction of ore particles 100

near the flat face, thereby providing for but a very small efficiency in the field. To decrease the strength of such field by increasing the distance would not only affect the particular gap in question, but also the other gaps or zones, in addition to requiring the employment of greater power. And where the zones are variable, as by adjustment of the pole pieces, toward each other, as where for instance, the parts are carried by a rotating carrier, adjustment of any or all of the edges could only be had when the apparatus is at rest, so that where the structure is employed for magnetic ore separation, adjustments can be had only under such rest condition; where, therefore, proper adjustment can only be obtained by testing the ore material passing through the zones it will be obvious that there is a large amount of time wasted due to the required stoppages of apparatus where the adjustment is not had at once.

My present invention aims to not only overcome the objectionable features indicated above, but in addition to increase the efficiency of apparatus employing magnetic fields by making them more flexible and capable of uses heretofore not possible. For instance, I am able to produce the results indicated by the following, where the invention is employed in connection with magnetic ore separators: (1) The division of the field of a magnet pole into zones of different strengths for the separation of materials of different permeability from each other. (2) The adjustment of different zones in the same field without altering the distance between opposed poles. (3) The adjustment of different zones in the same field by varying the reluctance of the individual paths. (4) A predetermination of the ratio of the different zones to one another. These may be considered as a few of the objects of the present invention.

Therefore, to these and other ends, the nature of which will be readily understood as the invention is hereinafter disclosed, my invention consists in the improved construction and combination of parts hereinafter fully described, illustrated in the accompanying drawings and particularly pointed out in the appended claims.

In the accompanying drawings, in which similar reference characters indicate similar parts in each of the views—Fig. 1 is a fragmentary view, partly in section, showing a magnetic field divided into zones, with the upper pole in the form of a secondary magnet, the field being shown as provided with three zones of different strengths. Fig. 2 is a similar view showing a modification of the idea, four zones being provided, both pole pieces being arranged in accordance with my invention. Fig. 3 is a similar view, also showing four zones and illustrating a

secondary magnet, the lower pole piece being shown as extending axially of a vertical magnet. Fig. 4 is a similar view, showing a different arrangement of the means for varying the strength of the gaps. Fig. 5 is a similar view, showing both pole pieces formed in accordance with my invention, this particular type providing for the greatest variance in gap strengths. Fig. 6 is a similar view illustrating a known form of structure for producing the result. Fig. 7 is a view of a still further modification of my idea, the view also having illustrations for the purpose of showing comparisons with Fig. 6.

In a magnetic circuit having a constant magneto-motive force, the flux density depends on the total reluctance of the circuit traversed, every air gap representing a large reluctance relative to an iron-circuit proportional to the length of the gap; obviously, therefore, variations in the length of the air gaps affect the flux density therein. As heretofore pointed out, however, variations in density provided by changing the length of the air gap between the poles, is disadvantageous, some of the reasons for which being heretofore set forth. To avoid these objections, I provide for retaining the air gaps in a constant length by introducing an additional reluctance in the circuit at any point independent of such gap for the purpose of reducing the flux to the desired strength, on the principle that a magnetic circuit can be shunted by an additional path of different reluctance, producing a stronger main path and weaker shunt-path and rendering it possible to provide more than one separating-gap. It is on this principle that I base my invention, and for convenience, I place all shunt-paths in the pole shoe of one or both poles; in this manner, the shunt-paths are as short as possible and avoid a leakage of flux. This idea can be provided in many forms, a few of which are indicated in the drawings. For the purpose of explaining the invention, I will use, for example, the showing of Fig. 1, in which 10 represents a horizontal magnet with a vertically rising pole shoe 11 opposing an edge of a secondary magnet 12 located thereabove. Additional magnetic features or members 13 and 14 are secured to the shoe 11, as by bolting, these magnetic members being spaced from the shoe 11 and from each other, being in opposition to opposing edges of the magnet 12, this form disclosing a structure providing three different zones, traversing which, for the purpose of illustration, I have shown a conveyer 16 such as would be provided in connection with magnetic ore separators. For convenience in interpreting the invention, I have shown the several poles 11, 13, and 14 as separated by insulation 15. This, however, is simply for the

purpose of indicating a cross-section of a gap between the several pole pieces, the showing being that of insulation, but this is, as before stated, simply to give a graphic comparison of what are intended as air gaps, the insulation of the electrical art being unknown, so far as I am aware, in magnetic circuits. The insulation is intended to represent a suitable reluctance, whose permeability is unity, and this reluctance can be provided in any desired manner.

It should be noted, that in a preferred form of my invention, the bolts by means of which the magnetic members 13 and 14 are secured to the pole shoe 11 are of non-magnetic material in order that an iron-circuit between these separated members is prevented, excepting under conditions presently described.

As will be readily understood, in this construction there are provided three paths for the flux to travel, the first being that between the shoe 11 and the opposing edge, this zone being of the greatest strength by reason of the fact that there is provided the smallest reluctance of the circuit, viz., the length of the gap between opposing poles; the second path is that provided between the member 13 and its opposing pole face of the secondary magnet 12; in this zone, the same amount of reluctance is provided in the separating gap (the space between the opposing poles) and additionally the reluctance provided by the spacing between the pole shoe 11 and the member 13, this increase in reluctance acting to decrease the strength of the zone in question, without, however, affecting the angle of convergence of the lines of force in the field or gap. The third zone provided between the member 14 and its opposing edge of the secondary magnet has its strength decreased from both of the other zones by reason of the fact that the flux path traverses both reluctance gaps 15 as well as the field gap. From the above, it will be seen that in each zone, the distance between the opposing pole faces is the same, providing similar angles of convergence in connection with each zone, as shown, for instance, in Fig. 7, the zones, however, being of different strength with that of the pole shoe 11 which is integral with the magnet core, as the maximum, the zones decreasing in strength proportionately to the amount of additional reluctance provided within the circuits. Obviously, the strength of the several zones can be readily determined by knowing the section of the reluctance gaps between the separated members. However, the strength of any auxiliary zone can be readily increased without affecting the distance between the opposing poles of the fields by providing an iron-path between the members. This path may be formed in any suitable manner, any magnetic material be-

ing employed and by controlling the cross-section of the material increase in strength can be readily controlled. For the purpose, the magnetic material may be in the form of blocks, sheets, or even wires, the purpose being to provide a path of less reluctance than the reluctance gaps, through which path the flux flows more readily and thus increases the strength of the circuit passing through the members. In Fig. 1 I have shown a member of this type at 18. As will be obvious the strength adjusting operation provided by the member 18 can take place without affecting the operation of the separator; and it will also be obvious that it will only be necessary to change the cross-sectional area of such member to vary the strength, so that variations can be made for testing purposes while the apparatus is in operation and proper strength to produce the best results quickly obtained.

As will be obvious, this idea may be employed in various forms of construction. For instance, in Fig. 2 the secondary magnet is replaced by a similar construction to that shown at the bottom, the auxiliary members being of different cross-sectional size and obviously providing for a different cross-section of the reluctance gap. This particular construction provides a greater variance in zone strength than in the form shown in Fig. 1. In this form, each zone beyond the inner one represented by the shoe 11 is subjected to the reluctance of two spaces instead of but one as in the structure of Fig. 1, and in addition, the successive members and the spaces therebetween forming the reluctance gaps are reduced by shortening thereby increasing the reluctance for the individual shunt circuit; in this figure I also show the application of the members 18 for the purpose of adjusting the zone strength.

In Fig. 3 I show a somewhat similar arrangement in connection with a magnet having a vertical axis, the opposing pole being provided by a secondary magnet, as in Fig. 1. In this form, as in Fig. 2, the members are of successively decreased length to increase the reluctance. In this form, a slightly different application of the bridging member 18 is shown, illustrating another way in which the adjustment in the zone strength may be accurately made.

In Fig. 4, a different arrangement of the same idea is provided, this arrangement giving a smaller ratio of strength between the strongest zone and the next than the second and third one, on account of the different ratio of reluctances between them. This arrangement may also be advantageously employed by reason of the ability to provide for finer adjustments in field strength, the dotted lines in the figure showing a different way in which the bridging members may be

employed, each of the auxiliary members being shown as magnetically connected to the pole member 11.

In Fig. 5 I show an arrangement which permits of an extreme difference in strength of the several zones, the reluctance between the same being increased to approximately their largest values. In this form, the shapes of the auxiliary members or poles is made so that their faces retain their most advantageous form, while the material in rear of the faces is cut away to increase the reluctance of the spaces, thus a high efficiency is insured for every one of the gaps at their greatest difference in strength. This form is probably of the greatest advantage, by reason of the fact that it affords the maximum range, and by the use of bridge members can be readily adjusted to increase the strength of the zones, it being understood, of course, that this arrangement does not provide for a decrease in the zone strength excepting by affecting the strength of the entire magnet as by reducing the number of ampere-turns.

Fig. 7 shows still another form in which this operation can be provided, this view being presented more particularly as showing one way in which to compare the effect to the effect produced by a different type of apparatus.

From the above, it will be readily understood that in each type, the length of the gaps is the same for each of the zones of any particular field; consequently, as shown in Fig. 7, the angles of convergence are similar in each zone, the only difference being in the zonal strength. Where a structure of this type is employed in magnetic ore separation, each zone becomes a separating gap and the ore conveyer intersects the field at substantially the same distances from the poles in each zone. Obviously, since the angles of convergence are the same in all of the zones the action of the circuits will be the same in each zone excepting for the strength of the zone, and as this strength is controllable as indicated, it will be obvious that a clean-cut separation will be provided.

While my invention is primarily intended for use in connection with magnetic ore separation, and I have disclosed it mainly in connection with such use, I believe the invention to be of broader scope and suitable for other purposes, however, and I therefore desire it to be understood that no specific application which may have been herein made shall be held to exclude other applications of the same general idea embodied herein, the structural and operative characteristics of which are the equivalents of those herein set forth, even though such apparatus may be utilized in different relations to effect a specifically different result.

Having thus described my invention, what I claim as new is:

1. In a magnetic field, means for establishing a magnetic circuit with a plurality of zonal gaps of substantially equal length, and means for varying the strength of the zones relative to each other by altering the reluctance between zones. 70

2. Means for forming zones of varying strengths in magnetic fields with substantially constant length of the zonal gap and including a field pole element having one or more members spaced apart to increase the reluctance of the magnetic circuit. 75

3. Means for forming zones of varying strengths in magnetic fields with substantially constant length of the zonal gap and including a field pole element having a member coöperating to provide a maximum zone strength and a magnetic member spaced 85 therefrom to increase the reluctance of the circuit through the second member.

4. Means for forming zones of varying strengths in magnetic fields with substantially constant length of the zonal gap and including a field pole element having a plurality of members, the faces of which are positioned to coöperate in providing separate gaps of equal length, the members being spaced apart to provide increasing reluctance to the magnetic circuit passing 90 through the members. 95

5. Means for forming zones of varying strengths in magnetic fields with substantially constant length of the zonal gap and including a field pole element having a plurality of members, the faces of which are positioned to coöperate in providing separate gaps of equal length, the members being spaced apart to provide increasing reluctance to the magnetic circuit passing through the members, said members being 100 normally out of magnetic contact. 105

6. Means for forming zones of varying strengths in magnetic fields with substantially constant length of the zonal gap and including a field pole element having a plurality of members, the faces of which are positioned to coöperate in providing separate gaps of equal length, the members being spaced apart to provide increasing reluctance to the magnetic circuit passing through the members, said members being normally out of magnetic contact, and independent means for magnetically connecting 110 115 two or more members together to adjust the strengths of the zones. 120

7. Means for forming zones of varying strengths in magnetic fields with substantially constant length of the zonal gap and including a field pole element having a plurality of members, the faces of which are positioned to coöperate in providing separate gaps of equal length, the members being spaced apart to provide increasing re- 125 130

luctance to the magnetic circuit passing through the members, said members being normally out of magnetic contact, and independent bridge members adapted to connect two or more members magnetically to adjust the zone strength.

8. In a magnetic field, means for establishing a magnetic circuit with a zonal gap of substantially constant length, and means for varying the strength of the gap independent of its length by varying the circuit reluctance.

9. In a magnetic field, means including opposing pole elements for establishing a magnetic circuit with a plurality of zonal gaps, and means for varying the strength

of the zones relatively to each other by altering the reluctance between zones in a pole element.

10. In a magnetic field, means including opposing pole elements for establishing a magnetic circuit with a plurality of zonal gaps, and means for varying the strength of the zones relatively to each other by altering the reluctance between zones in each of the pole elements.

In testimony whereof I affix my signature in the presence of two witnesses.
